ELECTRIC SNAP SWITCHES

Charles R. Smith, Mequon, Wis., assignor to Cutler-Hammer, Inc., Milwaukee, Wis., a corporation of Delaware

Application October 5, 1953, Serial No. 384,030

5 Claims. (Cl. 200—67)

This invention relates to electric snap switches and more particularly to improved actuating mechanisms for single pole, single throw snap switches.

An object of this invention is to provide an electric snap switch which is of simple construction and inexpensive to manufacture.

Another object is to provide a switch actuating mechanism for such switches, which mechanism can readily be produced in diminutive size to provide a snap-acting switch operating mechanism for miniature switches.

Another object is to provide a snap switch actuating mechanism which is readily adjustable at will so that the distance of travel of the actuating member can be reduced while still providing an abrupt snap movement in opening and closing the switch contacts.

A more specific object is to provide an actuating mechanism which effects hammer-blow snap opening of the switch contacts in response to a very short operating movement of the switch actuating member.

The novel features which I consider characteristic of my invention are set forth with particularity in the appended claims. The device itself, however, both as to its organization and mode of operation together with additional objects and advantages thereof, will best be understood from the following description of a specific embodiment when read in connection with the accompanying drawing, in which:

Figure 1 is a side elevational view of the device illustrating the actuating mechanism in closed contacts position;

Fig. 2 is a sectional view, taken along line 2—2 of Fig. 1;

Fig. 3 is a sectional view, taken along line 3—3 of Fig. 2, and

Fig. 4 is a fragmentary sectional view, taken along line 4—4 of Fig. 1.

Like reference characters indicate corresponding parts throughout the several figures of the drawings.

Referring to Fig. 1, it shows the invention comprising an approximately C-shaped molded insulating base 10. Attached to said base 10 as by means of a bolt 12, is a plate 16 having thereon a stationary contact 14. Bolt 12 also serves as a wiring terminal and employs a group of nuts 18 for the purpose of securely retaining a wiring lead (not shown). Any other suitable or well known means might be employed for electrically connecting a terminal wire with plate 16.

Fastened to said base 10 by means of bolt 20 are a stamped sheet metal contact carrier 22 and a stamped sheet metal flipper carrier 24. Said bolt 20 may also function, through the medium of nuts 18, as a wiring terminal as above-explained with respect to bolt 12.

Attached to said contact carrier 22 in any suitable or well known manner, such as by brazing, is a contact 26 movable into or out of cooperative engagement with stationary contact 14. Said contact carrier 22 is provided with an integral angularly bent portion by which it is mounted with respect to base 10 by said bolt 20; the angle

2

of said bent portion being such as to normally provide an inherent bias of movable contact 26 into cooperative engagement with stationary contact 14. Said contact carrier 22 is also provided with a depending tongue or projection 22^a sheared and bent downwardly from the main body portion of carrier 22 as shown in the drawings. Although not essential to successful operation of my invention, I prefer to bend at substantially a right angle, in one direction or the other, at least a portion of each of the longitudinal edges 22^b of carrier 22 to thus increase the strength and rigidity of those portions of member 22 which carry the movable contact 26 and the projection 22^b.

The flipper carrier 24 is also provided with angularly bent perforated end portion through which bolt 20 passes to attach the same to base 10, the angularity of said end portion being such as to provide an inherent bias which urges said flipper carrier 24 toward contact carrier 22. To prevent flipper carrier 24 from conducting electrical energy between plate 16 and terminal 20, the side of plate 16 opposite to that to which contact 14 is attached is provided with a suitable insulating covering, such as an insulating plate 28 which is fastened by any well known means, such as the lower clamping nut 18 and bolt 12 which secure plates 16 and 28 in position.

Flipper carrier 24 has at least a portion of its longitudinal edges 24^b bent at substantially a right angle, preferably downwardly, to provide greater strength and rigidity of carrier 24 over a major portion of its length. Two pairs of tabs 30 are bent downwardly from the main body portion of flipper carrier 24, as shown. Said pairs of tabs 30 are jointly provided with V notches for retention of a flipper member 32. Said flipper member 32 is made of spring steel and is formed at its opposite ends with tongue portions 32^a, 32^b (Fig. 4) to prevent accidental disengagement of said flipper member from said tabs 30. As best shown in Figs. 1 and 3, said flipper member 32 normally assumes an arcuate shape, its springy resilient character insuring retention thereof within the V notches of tabs 30. The portion of flipper carrier 24 immediately adjacent flipper member 32, as assembled, is provided with an opening 24^a to permit said flipper member 32 to flex upwardly, as shown in Fig. 3. Said opening 24^a also permits projection 22^a to extend downwardly beyond the flipper carrier 24, as shown in Fig. 1.

Threadedly positioned in base 10, and held in adjusted position by means of nut 34, is a set screw 36 which provides an adjustable abutment for contact with flipper member 32. A plate 38, preferably of metal, has a vertical slot formed therein (Fig. 3) whereby it is adjustably attached to base 10 by means of screw 40, and is properly positioned relatively to contact carrier 22 to restrict the upward movement of the latter to the desired degree.

An operating member 42 having a pair of legs slidably positioned in apertures within base 10, is provided for actuation of the switch mechanism. Legs 44 are attached to a connecting member 46 as by welding, and the lower ends of said legs normally jointly rest against flipper carrier 24, as shown in the drawings.

The inherent bias of contact carrier 22 normally provides for engagement of movable contact 26 with stationary contact 14, thus completing an electrical circuit through the switch mechanism. To effect interruption of such circuit by disengagement of the contacts, it is necessary that operating member 42 be moved inwardly. Such movement of member 42 causes flipper member 32 to contact set screw 36 due to downward movement of flipper carrier 24. Continued downward movement of flipper carrier 24 causes flipper member 32 to snap upwardly over-center due to contact thereof with set screw 36. Such upward over-center movement causes flipper member 32 to strike projection 22^a, thereby overcoming

the inherent bias of contact carrier 22 and moving the same upwardly against plate 38, as shown in Fig. 3. It is thus seen that disengagement of contact 26 from contact 14 is thereby effected.

Upon a predetermined reduction in the degree of pressure applied to member 42, the inherent bias of contact carrier 22 effects reengagement of the contacts. The contact carrier bias also simultaneously effects return of flipper member 32 to its normal position due to the force exerted by projection 22a on said flipper member 32, as shown in Fig. 1. It is realized that the particular operating member 42 shown in the drawings and described herein, is not essential to successful operation of the invention; the only requirement being to provide actuating means to move flipper carrier 24 against its inherent bias.

I have thus provided a switch mechanism which requires only a very short movement of the operating member to effect disengagement of the contacts. Moreover, I have provided a switch mechanism which can readily be produced in diminutive size to provide a snap action mechanism for miniature switches.

Although I have shown and described certain specific embodiments of my invention, I am fully aware that many modifications thereof are possible. My invention, therefore, is not to be restricted except in so far as is necessitated by the prior art and by the spirit of the appended claims.

I claim:

1. In a snap-action switch, in combination, a movable contact carrier biased in a given direction to effect engagement of a set of contacts, a movable flipper carrier biased in a direction opposite to said given direction and positioned relative to said contact carrier to cause said biases to urge said carriers toward each other, a resilient metal flipper member pivotally connected at each end thereof to said flipper carrier and normally bowed in one direction or the other with respect to the latter, said contact carrier having a projection extending toward said flipper member, an adjustable stationary abutment positioned adjacent said flipper member on the opposite side thereof from said contact carrier, and a switch actuating member to overcome said bias on said flipper carrier to cause said flipper member to contact said abutment thereby causing said flipper member to snap over-center and strike said projection on said contact carrier to move said contact carrier against its above-mentioned bias to thereby effect disengagement of said set of contacts.

2. In a snap-action switch, in combination, a movable contact carrier biased in a given direction to effect engagement of a set of contacts, a movable flipper carrier biased in a direction opposite to said given direction and positioned relative to said contact carrier so that said biases urge said carriers toward each other, a spring steel flipper member having knife-edge in pivotal engagement at each end thereof with said flipper carrier and normally bowed in one direction or the other with respect to the latter, said contact carrier having a projection extending toward said flipper member, an abutment positioned adjacent said flipper member on the opposite side thereof from said contact carrier, a switch actuating member to overcome said bias on said flipper carrier to cause said flipper member to contact said abutment thereby causing said flipper member to snap over-center and strike said projection on said contact carrier to move said contact carrier against its above-mentioned bias to effect disengagement of said set of contacts, said abutment being adjustable with respect to said flipper member to enable variation in the amount of travel necessary for said flipper carrier to effect over-center snap movement of said flipper member.

3. In a snap-action switch, in combination, a movable

contact carrier inherently biased in a given direction to effect engagement of a set of contacts and being provided with a projection extending in said given direction, a movable flipper carrier inherently biased in a direction opposite to said given direction and positioned relative to said contact carrier so that the respective biases urge said carriers toward each other, said flipper carrier having therein an opening to receive said projection on said contact carrier, a bowed flipper member having its opposite ends pivotally mounted on said flipper carrier substantially equidistantly from said contact carrier projection extending through said opening in said flipper carrier, an adjustably positioned abutment adjacent said flipper member on the side thereof opposite to said contact carrier, and a switch operating plunger to overcome said bias on said flipper carrier to cause said flipper member to contact said abutment thereby causing said flipper member to snap over-center to strike said projection on said contact carrier to move said contact carrier against its above-mentioned bias to effect disengagement of the set of contacts.

4. In a snap-action switch, in combination, a stationary contact, a movable contact carrier having a movable contact and being biased in a given direction to normally tend to effect engagement of said movable contact with said stationary contact, a movable flipper carrier inherently biased in a direction opposite to said given direction and positioned relative to said contact carrier to cause said biases to urge said carriers toward each other, a bowed flipper member pivotally engaged at each end thereof with flipper carrier, and bodily movable with the latter said contact carrier having a projection extending toward said flipper member, an adjustable stationary abutment positioned adjacent said flipper member on the opposite side thereof from said contact carrier, and a switch actuating member to overcome said bias on said flipper carrier to cause said flipper member to contact said abutment thereby causing said flipper to snap over-center and strike said projection on said contact carrier to move said contact carrier against its above-mentioned bias to thereby effect disengagement of said movable contact from said stationary contact.

5. In a snap-action switch, in combination, a stationary contact, a movable contact carrier having a movable contact and being inherently biased in a given direction to normally tend to effect engagement of said movable contact with said stationary contact, said contact carrier being provided with a projection extending in said given direction, a movable flipper carrier inherently biased in a direction opposite to said given direction and positioned relative to said contact carrier so that the respective biases urge said carriers toward each other, said flipper carrier having therein an opening to receive said projection on said contact carrier, a bowed flipper member having opposite ends pivotally mounted on said flipper carrier substantially equidistant from said contact carrier projection extending into said opening in said flipper carrier, an adjustably positioned abutment adjacent said flipper member on the side thereof opposite to said contact carrier, and a switch operating plunger to overcome said bias on said flipper carrier to cause said flipper to contact said abutment thereby causing said flipper to snap over-center to strike said projection on said contact carrier to move said contact carrier against its above-mentioned bias to effect disengagement of said stationary and said movable contacts.
